FLEXIBLE POCKET RECEPACLE

Douglas J. Broughton, Springfield, Mass., assignor to Buxton, Incorporated, Springfield, Mass., a corporation of Massachusetts

Application August 3, 1942, Serial No. 453,343

1 Claim. (Cl. 150—35)

This invention relates to flexible pocket receptacles, and more particularly to cases for carrying keys and automobile license, registration papers, and the like.

The principal object of the invention is to provide an improved construction for the above purpose and to so combine the various elements that all parts participate in the functioning of the receptacle as a whole, thereby simplifying the construction as well as securing a better and more effective mode of operation.

Other and further objects residing in the details of construction and in the preferred arrangement of the parts will be made apparent in the following specification and claim.

While the invention is applicable to general purpose key cases it has special application to relatively small cases intended for automobile use in which space is provided for a limited number of keys such as the ignition key, the luggage compartment key and two garage keys. For purpose of illustration such as specialized auto key case is shown in the accompanying drawing in which:

Fig. 1 is a front elevational view of the closed case;

Fig. 2 is a top view of the case as shown in Fig. 1;

Fig. 3 is a front elevational view of the case opened to give access to the keys;

Fig. 4 is a fragmentary view similar to Fig. 3 but with the case further opened to give access to the license and registration papers;

Fig. 5 is a sectional view substantially on line 5—5 of Fig. 3;

Fig. 6 is a diagrammatic view showing in exaggerated form the permitted movement of certain of the parts under conditions of use;

Fig. 7 is a detail view on a larger scale showing one of the hinge members, taken substantially on line 7—7 of Fig. 4; and

Fig. 8 is a fragmentary elevational view of a modified form on a smaller scale.

Referring to the drawing, 10 designates the case generally which is formed of flexible material, preferably leather. The case includes a rectangular back member indicated at 11 to which closure flaps 12 and 13 are hinged, one at each side of the back member. Preferably flaps 12 and 13 are integral with the back member and the hinge action of the flaps is secured by lines of fold as indicated at 14 and 15.

A flap 16 is hinged to the upper edge of back member 11 and for reasons set forth flap 16 is preferably relatively short, that is not more than half the vertical length of the back member 11. Flap 16 is also preferably integral with back member 11 and its hinged connection therewith is provided by folding as indicated at 17. Flap 16 is provided adjacent the fold line

17 with suitable means, generally indicated at 18, for supporting keys. The key supporting means may take any desired form, that shown being more fully disclosed in the patent to Boden 5 2,114,172, issued April 12, 1938. Preferably the key supporting means includes a rigid member extending transversely of the case, such means being provided, in the key supporting means shown, by the metal cylinder 19 to which the individual key retaining members 20 are attached.

A solid leather flap 21 is hinged to the bottom edge of back member 11. Flap 21 may be hinged to the member 11 in any suitable way but preferably as shown it is connected to the

15 back member by an extension 22 of flap 21 which is folded on itself as at 23. The extension 22 is stitched adjacent its folded edge to the lower edge portion of back member 11 as indicated at 23', leaving a free edge portion 24 overlying the 20 body of the flap. Portion 24 overlaps and is cemented or otherwise secured to the edge portion of a transparent panel 25 which is substantially coextensive with flap 21, the opposite end of panel 25 being suitably secured to the under side of a short folded-over extension 26 at the 25 free end of flap 21. The space between flap 21 and panel 25 provides a compartment 27 to accommodate license or registration papers, visible through the transparent panel 25. Compartment 27 is open at both side edges and preferably 30 I increase the paper carrying capacity by hinging two additional compartments 28 and 29 one to each side edge of flap 21. These additional compartments are formed of inner and outer 35 walls 30, 31 and 32, 33 respectively, which are preferably formed of transparent material. Walls 30 and 31 are secured together along their top, bottom, and outer side edges by bindings 35 and wall 30 is hinged at its inner edge, a side 40 edge of flap 21, by a side extension 36 of the flap to which extension wall 30 is cemented or otherwise secured. Compartment 28 is thus provided with an open side adjacent to and in line with an open side of compartment 27 when 45 wall 30 is positioned in the plane of flap 21. Walls 32 and 33 are secured together at their top and bottom edges only, as by binding 37, and wall 32 is hinged to the other side edge of flap 21 by a side extension 38 of the flap to which 50 extension wall 32 is cemented or otherwise secured. When compartments 27, 28, and 29 are unfolded to lie in a common plane, as shown in Fig. 4, license or registration papers in unfolded or only partially folded condition may be inserted in the compartments 27, 28 and 29 through the opening at the free side edge of the latter. Compartments 28 and 29 are foldable in superposed relation on flap 21 and flap 21 is then folded onto back member 11 to position 55 the compartments 27, 28 and 29 between back

60 the compartments 27, 28 and 29 between back

member 11 and flap 21, as shown in Figs. 3 and 5. The exposed face of flap 21 is provided with one element 40 of a fastening member, the other element 41 of which is carried by flap 16, both elements being positioned substantially on the vertical center line of the case. When elements 40 and 41 are engaged the license and registration compartments are held securely concealed and protected as shown in Figs. 3 and 5. Flap 21 and its associated parts serve as a transverse stiffening reenforcement for the case. The advantages of a reenforcement against sidewise collapse of the case is well recognized and for best results such reenforcement has been hinged at the top of the case with its lower end free as shown, for example, in the prior Buxton Patent 1,443,937 issued January 30, 1923. The freedom of movement allowed the reenforcement by its connection to the case at the upper end only has a substantial advantage in permitting the case to adjust itself to the key load, and permit needed relative movement of the parts, so that the key case forms a flexible package rather than a stiff rigid "box" when carried in the pocket of the user. I have found that the reenforcing member, in the present instance the flap 21 and its associated parts, may be secured against swinging movement outwardly of the case and yet be afforded sufficient freedom of sidewise movement for satisfactory operation by a proper arrangement of the fastener means, and this preferred arrangement is shown in Figs. 1 to 6 of the drawing. The preferred arrangement employs a fastener which permits relative pivotal movement of flaps 16 and 21 in the plane of their fastening about the fastener as a center, accompanied by a sidewise movement of the fastener. The conventional post and socket snap fastener affords the desired pivotal movement. Preferably the snap fastener is placed above the transverse center of the case and above the line defined by the lower ends of key retaining members 20. The character of the movement obtained is indicated, in exaggerated degree, in Fig. 6 where the respective extreme positions are shown in heavy and light lines. The relative pivotal movement of the flaps causes a distortion of the hinges and the degree of sidewise movement may therefore be controlled and limited by the flexibility of the hinge connections of flaps 16 and 21 to the back member 11. The greater distance between fastening 40-41 and the hinge of flap 21 as compared with the relatively short distance between fastening 40-41 and the hinge of flap 16 makes it desirable to employ the stiffer hinge construction for flap 21 afforded by the stitched folded extension 22 as previously described.

A somewhat less desirable arrangement is shown in Fig. 8 where the flap 16 is shown lengthened as at 16a to position fastener 40-41 in substantially the same relative position to the bottom of the case as it bears to the top of the case in the previously described arrangement. The arrangement of Fig. 8 gives adequate sidewise movement of the flaps 16a but the short flap 16 gives better support to the keys since the shortness of the flap minimizes twisting out of its plane.

In either form the fastener 40-41 is offset (above or below) the transverse center line of the key case. The heads of the keys form the

bulkiest part of the assembly of keys and the line of greatest bulk therefore occurs slightly below the lower ends of the key retaining members, and in practice lies substantially along the transverse center line of the case. The offsetting of the fasteners 40-41 from this line makes it possible to utilize the flap closure arrangement shown in Buxton Patent 1,966,429, issued July 17, 1934, which provides secure closing of the upper end of the case and keeps the keys in orderly position in the case. The arrangement of fastener 40-41 as in Figs. 1 to 6 increases the security of the closure. As best shown in Figs. 1 and 3, the closure flaps 12 and 13 are provided with snap fastener elements 45 and 46 which are positioned to engage at a point offset transversely from the point of engagement of fastener 40-41. Fastener 45-46 permits relative pivotal movement of flaps 12 and 13 in the plane of connection and at a point above the main bulk of the keys. Both fasteners 40-41, and 45-46 being above the line of the greatest bulk of the keys tend to keep the keys from upward movement and the upper portion of the case is drawn across fastener 40-41 by fastener 45-46 to more effectively take up any slack between the rigid cylinder 19 and the bulk of the key heads adjacent the lower ends of key retaining members 20. Placing the fastener 40-41 below the line of greatest bulk as in Fig. 8, secures substantially all the advantages mentioned above except that in the lower position it does not share in securing a tight closure of the case and in keeping the keys in position in the closed case.

While for best results both fasteners are offset from the transverse center line of the case, as shown, if either one is so positioned between the rigid member 19 and the line of the key heads, it will afford a reasonably satisfactory preventive of upward movement of the keys in the closed case.

What I claim is:

A flexible pocket receptacle for keys and registration papers and the like, comprising a case forming member including a rectangular back member and closure flaps hinged to the side edges thereof, a flap hinged to the upper edge of the back member and folded thereon, a key retaining member carried by the last named flap adjacent its hinge, a flap, for reenforcing the case against sidewise collapse, hinged to the bottom edge of the back member, said reenforcing flap folded beneath the key-carrying flap and extending upwardly to a line adjacent the hinge of the latter flap, a paper-carrying pocket carried by the reenforcing flap and available when the reenforcing flap is swung downwardly from beneath the key-carrying flap leaving the latter within the confines of the case, and fastening means for releasably connecting the key-carrying and reenforcing flaps together when both said flaps are folded into the case, said key-carrying flap being shorter than the reenforcing flap, said fastening means connecting said flaps at a point above the centerline of the case and permitting a limited sidewise movement of the reenforcing flap and short key-supporting flap relative to each other and to the back member of the case.
